(57) **CLAIM**

The ornamental design for a light emitting tool chuck, as shown and described.

DESCRIPTION

FIG. 1 is a bottom plan view of a light emitting tool chuck showing my new design;

FIG. 2 is a top plan view of the light emitting tool chuck;

FIG. 3 is a front elevation view of the light emitting tool chuck;

FIG. 4 is a rear elevation view of the light emitting tool chuck;

FIG. 5 is a left side elevation view of the light emitting tool chuck; and,

FIG. 6 is a right side elevation view of the light emitting tool chuck.

The broken lines in the drawings depict unclaimed environmental subject matter.
